Primary Examiner — Darlington Ly*Assistant Examiner* — Daniel J Domino(74) *Attorney, Agent, or Firm* — Pearl Cohen Zedek Latzer Baratz LLP(57) **CLAIM**

The ornamental design for a game tile, as shown and described.

DESCRIPTION

FIG. 1 is a bottom, front, right side perspective view of a game tile;

FIG. 2 is a front view thereof;

FIG. 3 is a rear view thereof;

FIG. 4 is a right side view thereof;

FIG. 5 is a left side view thereof;

FIG. 6 is bottom view thereof;

FIG. 7 is a top view thereof;

FIG. 8 is a bottom, rear, left side perspective view thereof;

FIG. 9 is a bottom, front, right side perspective view of a game tile with an environmental surface ornamentation;

FIG. 10 is a front view thereof;

FIG. 11 is a rear view thereof;

FIG. 12 is a right side view thereof;

FIG. 13 is a left side view thereof;

FIG. 14 is bottom view thereof;

FIG. 15 is a top view thereof; and,

FIG. 16 is a bottom, rear, left side perspective view thereof.

The broken lines shown in the drawings represent portions of the game tile which form no part of the claimed design.
